2 SHEETS—SHEET 2.

UNITED STATES PATENT OFFICE.

LONNIE THOMAS PENNY, OF RALEIGH, NORTH CAROLINA.

CAR-DOOR-OPERATING MECHANISM.

1,393,959.

Specification of Letters Patent.

Patented Oct. 18, 1921.

Application filed March 3, 1920. Serial No. 362,960.

To all whom it may concern:

Be it known that I, LONNIE T. PENNY, a citizen of the United States, residing at Raleigh, in the county of Wake and State 5 of North Carolina, have invented certain new and useful Improvements in Car-Door-Operating Mechanism; and I do hereby declare the following to be a full, clear, and exact description of the invention, such as 10 will enable others skilled in the art to which it appertains to make and use the same.

This invention relates to improvements in sliding doors for railway cars, or more especially to doors for freight cars, cattle cars 15 and other similar structures.

Heretofore, in the operation of opening and closing the sliding doors of freight cars or similar structures with door opening and closing means operable only from the exterior, considerable difficulty has been experienced. In the ordinary type of car door in use at the present time the sliding door is supported at the top by means of wheels upon a track and is held in position at the 25 bottom by a series of two or more L-shaped retaining means and is fastened in a closed position by only one device and this is hand operated. The above type of door has in practice proven very inefficient, having developed various defects, such as jumping the track, becoming jammed, warped, swinging out at the base, and failing to be readily secured, with consequent financial loss.

35 Various attempts have been made to simplify the operation of the above type of cumbersome car door, such as the provision of leverage means whereby the door may be operated with a smaller degree of physical 40 strength as well as the substitution of other types of doors but only a very slight degree of success has heretofore been attained.

The objects of my invention are to overcome the foregoing difficulties and to provide simple, efficient and reliable means whereby the operation of a car door is rendered the subject of but a moment's attention and then with the expenditure of only the smallest amount of energy.

50 Other objects of my invention are to provide improved means for mounting a car door for lengthwise movement, to aid in the operation of the door, to provide an automatically operated latch for holding the door in a closed position and a second means whereby the door will remain locked in a

closed position if the latch becomes for any reason broken or inoperative.

The invention will first be hereinafter described, with reference to the accompanying drawings, which form a part of this specification, and then pointed out in the claims at the end of the description.

In said drawings,

Figure 1 is a side elevation of a portion 65 of a freight car provided with a door in open position and mounting, securing, locking and operating means therefor in accordance with my invention;

Fig. 2 is a like view with the door in a 70 closed, locked position and with portions of the upper and lower retaining means broken away.

Fig. 3 is a fragmentary sectional view looking in the direction of the arrows, on the 75 line 3—3 of Fig. 2 showing the position of the supporting wheels with reference to the U-shaped retaining track when the door is in a locked position;

Fig. 4 is a sectional plan view looking in 80 the direction of the arrows on the line 4—4 of Fig. 2;

Fig. 5 is a like view on the line 5—5 of Fig. 2 showing the stop engaging means for maintaining the door in a closed position;

Fig. 6 is an end view of the latch fastening means in the position shown in Fig. 2.

Referring to said drawings, in which the same reference numerals are used to designate corresponding parts throughout the different views, 1 indicates the wall or side of a freight car to which is rigidly attached a retaining plate 2, by means of a series of braces 3. Between this retaining plate and 90 the side of the car is located a track 4, U-shaped in cross section which serves as the retaining means for the disk wheels 5 which support by means of T-shaped braces 6, the door 7, of the car 1. The track 4 is pivotally mounted upon a series of bolt extensions 8, which serve as bearing shafts for the links 9. Near the end of the U-shaped track, over which the door is supported when in a closed position, is a stud 4' which 105 serves as a wheel contacting means for lowering the track when the door is moved to a closed position. Two stop members 4" located beneath the U-shaped track adjacent each end thereof serve to prevent the track 110 from being lowered beyond a predetermined point. Pivoted at the end of the U-shaped

track 4 by means of a bolt or rivet 10 is a lever 11 fulcrumed upon a stud 12 which is fixed to the side of the car. The lever 11 has a longitudinal slot 13 which allows a reciprocating play, one end of which slot is eccentrically enlarged to serve as a retaining means for the stud 12 to prevent the pivotally mounted track from jarring to a position which will free the wheels supporting the door. Attached to the door of the car are a series of stop members 14 which are positioned behind a second series of stop members 15, carried by the retaining plate 2 when the door is in a closed position. At the center of the door adjacent the bottom thereof is attached a member 16, the outwardly extended portion of which is adapted to rest upon the upper surface of the retaining plate 2 to support the door when the same is in a closed position, thereby freeing the disk wheels 5 from the weight of the door. A second retaining plate 17 suffices to maintain the top of the door in proper position when the same is open or closed. A handle 18 is located near the center of the door directly above the member 16. A second handle 19 is located near the inner side of the door adapted for use in operating the door as is also the handle 18. Pivotally supported in the U-shaped end of a member 20 affixed to the door is a latch 21 which projects beyond the inner edge of the door at a point near the center thereof, said latch having an outwardly extended portion 22 (as best seen in Fig. 6); said portion having a cam face 23, and a shoulder 24. In co-operative relationship with the latch 21, and at a suitable distance from one side of the door opening is a catch 25 having a cam face 26 and a cut away portion 27 (as seen in Fig. 6) adapted to be engaged by the shoulder 24 of the latch 21. Also located at one side of the door opening is a member 28 which has a tapered end 29 which projects over the edge of the door when the same is in a closed position serving to keep the edge of the door from bulging outwardly when pressure is applied from the inside of the car.

The door is very simple and efficient in its operation for when it is in an open position notwithstanding the position of the latch 21, force applied to the handle 18 or 19 in the direction of the opposite door facing will cause the door, supported by means of the T-shaped brackets 6 upon the disk wheels 5, to ride along the U-shaped track 4 and upon the contacting of the pin 4' by the forward disk wheel the track is thrown to a lowered position (as seen in Fig. 2); the latch at the same time having ridden over the catch 25, by means of the cam faces 23 and 26 respectively, and securely locked, and the stops 14 having come to a position directly behind the cor-

responding stops 15, thus securing the door in a doubly locked position while the same is supported upon the plate 2 by means of the member 16 attached to the door.

Located along the bottom of the U-shaped track are a series of apertures 30 as shown in dotted lines in Fig. 1, adapted to allow water, snow or the like, which may have collected in said track, an exit.

Having thus described my invention, what I claim as new and desire to secure by Letters Patent is:

1. In combination, a car door, supporting, retaining and locking means therefor, said supporting means comprising rollers, means engaging said rollers for elevating and lowering the supporting means, and a further means whereby the door is prevented from being opened until said supporting means is in an elevated position. 85
2. In combination, a car door, supporting and retaining means therefor, said supporting means comprising rollers, means engaging said rollers for elevating and lowering said door, and a further means whereby the door is prevented from being opened until it is in an elevated position. 90
3. In combination a car door, a latch thereon, wheels supporting said door, a track supporting said wheels and pivotally mounted upon bearing bolts, means whereby the track is lowered in a parallel manner when the door is moved to a closed position and a second means whereby the track is elevated in a parallel manner to open the door 100 and a rest upon said door for supporting the same when the door is closed, and a further means for preventing the opening of the door when the track is in a lowered position. 105
4. In combination with a car door, upper and lower retaining means, a pivotally mounted U-shaped track supporting the rollers of the door, stop members carried by said door adapted to contact corresponding stop members carried by the lower retaining means to prevent the opening of the door when the same is supported off its wheels, a lever for elevating the track, a latch adapted for co-operation with a catch 115 to lock the door, a supporting member adapted to support the door upon the lower retaining means when the track is lowered from under the wheels of the door, handles for opening and closing the door and a third 120 retaining means adapted to prevent the door from bulging when force is applied from the inside. 115
5. In combination a car door, a latch thereon, wheels supporting said door, a track having apertures in the bottom thereof for exit of water, said track supporting said wheels and pivotally mounted upon bearing bolts, means whereby the track is moved out of engagement with the wheels when the 125

door is moved to a closed position and a second means whereby the track is moved into engagement with the wheels to open the door and a rest upon said door for supporting the same when the door is closed, and a further means for preventing the opening of the door when the track is out of engagement with the wheels.

6. In combination, a car door supported

10 at its base by means of rollers upon a track and having means for automatically freeing its rollers from said track and automatically locking when moved to a closed position, said locking means comprising spaced members carried by said door adjacent its base.

7. In combination, a car door, means for elevating and lowering said door, a second means for preventing lowering of the door beyond a predetermined point, and supporting means comprising a track and rollers upon the track, said track being pivotally supported upon a series of studs and capable of being shifted out of and into engagement with the rollers of the door.

25 8. In combination, a car door, means for elevating and lowering said door, a second means for preventing lowering of the door beyond a predetermined point, door supporting means comprising a track and rollers upon the track, said track being pivotally supported upon a series of studs, and leverage means for throwing the track out of and into engagement with the rollers of the door.

30 9. In combination, a car door, means for elevating and lowering said door, a second means for preventing lowering of the door beyond a predetermined point, a supporting

track, and means for moving the track into and out of engagement with the door in a parallel manner.

10. In combination, a car door having upper and lower retaining means independent of its mounting, means for elevating and lowering said door, a second means for preventing lowering of the door beyond a predetermined point, supporting means comprising a track and rollers upon the track, means for moving the track into and out of engagement with the door, and a projection upon the door for seating upon the lower retaining means when the track is moved out of engagement with the rollers of the door.

11. In combination, a car door having upper and lower retaining means independent of its mounting, means for elevating and lowering said door, a further means for preventing the lowering of the door beyond a predetermined point, supporting means comprising a track and rollers upon the track, means for moving the track into and out of engagement with the door, and tapered projections on the door adapted for coöperation with stop members on the lower retaining means to prevent opening of the door when supported off its rollers, and further adapted to maintain a tight fit between the door and the side of the car.

In testimony whereof I affix my signature in the presence of two witnesses.

LONNIE THOMAS PENNY.
